UNITED STATES PATENT OFFICE

CHARLES F. WRIGHT, OF AKRON, OHIO, ASSIGNOR TO THE DIAMOND MATCH COMPANY, OF BALTIMORE, MARYLAND, A CORPORATION OF MARYLAND

TRANSFER-TRAY FILLING MECHANISM FOR MATCH MACHINES

Application filed August 25, 1931. Serial No. 559,202.

This invention relates to machines for making matches, having reference especially to that class of machines wherein is employed an endless match carrier from which the matches are discharged in succeeding rows.

The principal object of my invention is to provide simple and efficient means whereby transfer trays can be associated with the match carrier and advanced successively to and across the path of discharge of the matches or splints in such manner that each tray is effectually filled with superposed rows of matches or splints.

With this and other objects in view my invention comprises features of novelty and combinations of parts which, in a preferred form, will be hereinafter described, the scope of the invention being expressed in the appended claims.

20 In the drawings—

Figure 1 is an elevation of the discharge end of a match machine equipped with transfer-tray filling mechanism embodying a form of my invention.

25 Fig. 2 is a transverse vertical section of the machine, as on the line 2—2 of Fig. 1.

Fig. 3 is a horizontal section, as on the line 3—3 of Fig. 2, showing the mechanism for actuating the tray-feeding chains.

30 Fig. 4 is a detail of ratchet and pawl devices included in the chain actuating mechanism.

Fig. 5 is a detail of an eccentric for operating the ratchet and pawl devices.

35 Fig. 6 is a longitudinal vertical section, enlarged, of one of the chain guides, a portion of the feed chain therein, a portion of the transfer tray engaged by the chain, and adjacent juncs.

40 Fig. 7 is a horizontal section, as on the line 7—7 of Fig. 6.

Fig. 8 is a vertical section through the match carrier and a transfer tray associated therewith, showing a portion of one of the tray-feeding chains.

Fig. 9 is a partial plan of a slotted bottom slide for a transfer tray.

45 Referring to the drawings, 10 designates 50 a portion of the main frame of a match ma-

chine; 11 designates the main shaft, and 12 designates a portion of an endless carrier into which the ends of successive parallel rows of out projecting splints S are inserted at one location and transported thence through the match making path to another location where the rows of finished matches are successively discharged.

The form of match carrier herein shown 55 comprises an endless chain of hingedly connected perforated plates having marginal gear racks 13 in mesh with actuating gears 14 included in a suitable gear train 15. The shaft 16 of one of the gears 14 is appropriately driven through suitable bevel gearing 17 60 from pin wheels 18 which are intermittently actuated by cams 19 on the main shaft, as usual.

In the type of machine selected for illustration the rows of splints are contained in a 65 suitably-disposed hopper 20 from which they are transferred row by row to the carrier 12 by a horizontally reciprocating setting head 21 mounted beneath the hopper, and the 70 matches are ejected row by row from the carrier by the punches 22 of a horizontally reciprocating punch head 23, under the control of a cam on the main shaft.

75 Fig. 24 designates a match transfer-tray into which the matches are delivered in close-lying rows by the reciprocating punch head of the match machine. Each tray preferably 80 consists of a light rectangular structure of sheet metal having two narrow sides 25, a back 26 and a slidable bottom plate 27, which plate may be readily withdrawn to permit the assembled matches to drop from the tray into a suitable receptacle after the tray has been 85 filled by and removed from the match machine. The plate 27 is formed with spaced transverse slots 28 which extend inwardly a suitable distance from the open side of the tray, the purpose of which slots will presently 90 appear.

A tray is supported in vertical position adjacent the carrier at the discharge end of the match machine, and is moved downwardly in timed relation to the travel of the carrier in a manner to position the tray for the proper 95 reception of the matches discharged from the 100

carrier by the punch head, the tray when filled being removed and immediately succeeded by an empty tray, and so on.

The preferred form of mechanism herein illustrated for supporting and feeding the transfer-tray is as follows:

29 designates two endless chains arranged adjacent to and parallel with the respective sides of the vertical run of the match carrier at the discharge end of the match machine. These chains pass about upper and lower sprocket wheels 30, 31, respectively. The upper sprocket wheels 30 are fast on shafts 32 having their bearings in suitably-disposed brackets 33 on the frame structure 34 of the match machine, and the lower sprocket wheels 31 are loose on shafts 35 fixed in brackets 36 on the frame structure. The shafts 32 have fast thereon bevel gears 37 in mesh with similar gears 38 on a transverse shaft 39 having its bearings in extensions 40 of the brackets 33. This shaft 39 has loose thereon at one end a pawl-disk 41 which is operatively connected by means of a rod 42 with an eccentric 43 fast on the main shaft 11 of the machine. The pawl 44 on the disk 41 engages a ratchet 45 fast on the shaft 39, and hence during each rotation of the main shaft 11 the shaft 39 is advanced one tooth of the ratchet. The ratio of the bevel gearing is such that in each step of the shaft 39 the chains 29 are advanced a distance much less than that between two adjacent rows of matches on the carrier. For example, in the machine selected for illustration the carrier in each step moves a distance of one-half inch while the chains 29 move a distance of .045 of an inch.

The inner vertical runs of the chains 29 travel downward, and as they approach and pass the discharge of the match machine they are guided by and between vertical guides 46 which are fixed adjacent the respective sides of the match carrier. Each of these guides in the present instance comprises a longitudinally channelled bar which is secured to a block 47 on a cross-bar 48 supported by the main frame.

Loosely fitted in the lower portion of the guideway and in parallelism with the adjacent run of the chain is a horizontally movable spring-pressed bar 49 which bears against the opposing inner portion of the chain 29 and tends to press it inward. The bar 49 is about equal in length to that of a match tray and the upper end of such bar is located just below the horizontal plane of the discharge punches. This bar 49 is supported by a series of spaced pins 50 which project therefrom through orifices in the outer wall 51 of the adjacent guide 46, the outer ends of the pins being threaded to receive nuts 51. Encircling the pins, between the bars 46, 49 are springs 52 which urge the bar 49 against the opposing chain. By properly adjusting the nuts 51 on the outer ends of the pins 50

the spring pressure on the bars 49 can be nicely regulated.

The guide bars 46 support a vertical wall plate 53 in close relation to the path of the match carrier in the space between the punch head and the lower ends of the pressure bars 49, which plate thus serves as a backer member to maintain the contained matches in the tray as the tray passes and progresses below the punch head. The upper edge of this plate is preferably notched or serrated, as at 54, to afford guide spaces for the tails of the matches as they are ejected by the punch head and delivered to the tray, and such upper edge is also provided with a series of spaced parallel blades 55 which extend outwardly into the path of the trays and afford partitions effective to prevent undue lateral displacement of the matches deposited in the tray. These blades are spaced correspondingly with the slots 28 in the bottom plate 27 of the tray, thus permitting the free downward travel of the tray with its open front in close relation to the outer face of the match carrier.

The dimensions of the match tray are such that it can be arranged between the inner runs of the chains 29 above the plane of the discharge punches, with the bottom member 27 of the tray inserted between two adjacent rows of projecting matches in the carrier. Hence the tray is supported by a row of matches held in the carrier, and is uniformly advanced toward the punch head at the same speed as the match carrier travels. When the supporting row of matches for the tray reaches the plane of the punches such row is ejected from the match carrier, thus releasing the tray from the feeding movement of the carrier. At this juncture the lower portion of the tray enters the grasp of the inwardly-pressed portions of the intermittently-moving side chains 29, and the latter thereupon carry the tray downward correspondingly with the discharge of succeeding rows of matches from the carrier by the punch head, but with steps shorter than those of the carrier. The ejected rows of matches are thus progressively deposited in close-lying relation within the tray until the tray has been filled, whereupon owing to the yielding gripping action of the side chains the tray can be readily grasped and slid out by the attendant.

By varying the resilient force of the springs 52 on the bars 49 and chains 29, the pressure of the chains on the interposed tray can be nicely adjusted to support the weight of the tray and its contained matches.

By virtue of the relatively short downward movements of the tray while it is being filled, the succeeding rows of matches are inserted in the tray in close relation and without "drop" and in consequence the heads of the contained matches bear on each other with

sufficient force at the back of the tray to maintain the splints in substantially uniform position, as indicated in Fig. 8, thus preventing the canting and irregular arrangement of the tails of the splints.

5 While a tray is being filled the attendant can readily apply a succeeding empty tray to the match carrier, with the bottom of the tray supported between adjacent rows of matches, which latter tray, owing to the different step movements of the match carrier and the chains 29, should be located a sufficient distance above the punch head, as indicated at A in Figs. 1 and 2, to insure the proper relation of the bottom of the empty tray to the discharge punches when the preceding tray has been filled or nearly so. In this way a practically continuous delivery of trays at the discharge end of the match machine can be maintained during the operation of the machine.

20 My invention is not limited to the details of construction herein shown as the mechanism may be modified within the principle of the invention and the scope of the appended claims; it being noted that the term "matches" as used in the claims is inclusive of splints.

I claim—

30 1. In a match machine having a travelling carrier from which rows of matches project, and means for discharging such rows successively from the carrier, a match transfer-tray open at the top and having a bottom member insertable between two adjacent rows of projecting matches above the path of the match discharging means, by which rows the tray can be supported in close parallel relation to the outer face of the carrier and moved correspondingly with the carrier to the discharge means, and means for engaging said tray and feeding it progressively downward when the row of tray supporting splints has been discharged from the carrier.

40 2. In a match machine having a travelling carrier from which rows of matches project, and means for discharging such rows successively from the carrier, a match transfer-tray open at the top and having a bottom member insertable between two adjacent rows of projecting matches above the path of the match discharging means, by which rows the tray can be supported in close parallel relation to the outer face of the carrier and moved correspondingly with the carrier to the discharge means, and means for engaging the vertical sides of said tray and feeding it progressively downward when the row of tray supporting splints has been discharged from the carrier.

50 3. In a match machine having a travelling carrier from which rows of matches project, and means for discharging such rows successively from the carrier, a match transfer-tray open at the top and having a member

insertable between two adjacent rows of projecting matches above the path of the match discharging means, by which rows the tray can be supported in close parallel relation to the outer face of the carrier and moved correspondingly with the carrier to the discharge means, and means including parallel chains for engaging the vertical sides of said tray and feeding it progressively downward when the row of tray supporting splints has been discharged from the carrier. 70

4. In a match machine having a travelling carrier from which rows of matches project, and means for discharging such rows successively from the carrier, a match transfer-tray open at the top and having a member insertable between two adjacent rows of projecting matches above the path of the match discharging means, by which rows the tray can be supported in close parallel relation to the outer face of the carrier and moved correspondingly with the carrier to the discharge means, chain guides arranged adjacent the respective sides of the carrier, parallel chains in said guides, means for actuating said chains in timed relation to the carrier, and means yieldably pressing such portions against the respective sides of the tray when the row of tray supporting splints has been discharged from the carrier. 80

5. In a match machine having a travelling carrier from which spaced rows of matches project, and means for discharging such rows successively from the carrier, a match transfer-tray open at the top and having a bottom member insertable between two adjacent rows of projecting matches above the path of the match discharge means, by which rows the tray can be supported in close parallel relation to the outer face of the carrier and moved correspondingly with the carrier to the discharge means, chain guides arranged adjacent the respective sides of the carrier, parallel chains in said guides, means for actuating said chains in timed relation to the carrier, pressure members arranged in said guides, and adjustable spring means urging said members against the opposing portions of the respective chains, whereby said chains are operative to grip and progressively move the tray when the row of tray supporting splints has been discharged from the carrier. 100

6. In a match machine having a travelling carrier from which spaced rows of matches project, and means for discharging such rows successively from the carrier, a wall plate arranged in front of the carrier and extending downward from the plane of the discharge means, a match transfer-tray open at the top and having a bottom member insertable between two adjacent rows of projecting matches above the path of the discharge means, by which rows the tray can be supported in close parallel relation to the outer 110

face of the carrier and moved correspondingly with the carrier to the discharge means, and means for engaging said tray and feeding it progressively downward when the row of tray supporting splints has been discharged from the carrier.

7. In a match machine having a travelling carrier from which spaced rows of matches project, and means for discharging such rows successively from the carrier, a wall plate arranged in front of the carrier and extending downward from the plane of the discharge means, the upper edge of said plate being serrated to afford supports for the tails of a row of discharged matches, a match transfer-tray open at the top and having a bottom member insertable between two adjacent rows of projecting matches above the path of the discharge means, by which rows the tray can be supported in close parallel relation to the outer face of the carrier and moved correspondingly with the carrier to the discharge means, and means for engaging said tray and feeding it progressively downward when the row of tray supporting splints has been discharged from the carrier.

8. In a match machine having a travelling carrier from which spaced rows of matches project, and means for discharging such rows successively from the carrier, a wall plate arranged in front of the carrier and extending downward from the plane of the discharge means, the upper edge of said plate being serrated to provide supports for the tails of a row of matches and having a series of spaced-apart outwardly-extending partition blades, a match transfer-tray open at the top and having a bottom member provided with spaced slots corresponding with the blades, said member being insertable between two adjacent rows of projecting matches above the path of the discharge means, by which rows the tray can be supported in close parallel relation to the outer face of the carrier and moved correspondingly with the carrier to the discharge means, and means for engaging said tray and feeding it progressively downward when the row of tray supporting splints has been discharged from the carrier.

9. A rectangular transfer tray for use in connection with a match machine having a match carrier, means for discharging succeeding rows of matches from the carrier and into the tray, and spaced partition strips extending outwardly at the discharge means, said tray comprising two narrow sides, a back and a slidably bottom plate having spaced transverse slots corresponding with the partition strips.

10. In a match machine having a travelling carrier from which spaced rows of matches project, and means for discharging such rows successively from the carrier, a match transfer tray supported in close parallel relation to the outer face of the carrier and movable

correspondingly with the carrier to the discharge means, and means for thereafter engaging said tray and feeding it downward with a relatively short step-by-step movement whereby the succeeding rows of matches discharged from the carrier are positioned in the tray in close parallel relation.

Signed at Barberton, in the county of Summit and State of Ohio this 21st day of August A. D. 1931.

CHARLES F. WRIGHT.
